SYSTEM FOR MIXING MOLASSES WITH FEED

Earnest M. Wetmore, Tonkawa, Okla.

Application February 27, 1956, Serial No. 567,936

5 Claims. (Cl. 146—106)

This invention relates to an improved system for mixing molasses with livestock feed.

For many years, and particularly after the advent of specially prepared, high-protein feed for cattle, it has been the practice to feed cattle roughage-type feeds (such as fodder and the like) mixed with molasses in order that the cattle will have sufficient bulk food to supplement the high protein diet. Due to the nature of molasses however, it is difficult to efficiently mix the molasses with the roughage-type feed. One method has been to spray molasses onto the roughage, either while the roughage is on the ground, or after it has been harvested and before it has been shredded or comminuted. The molasses mixed in this manner will frequently clog a comminuting apparatus, such as a hammer mill. Another and more widely accepted method of mixing the molasses with roughage has been to spray the molasses into a container or trough of comminuted roughage, while simultaneously turning the roughage to provide a distribution of molasses. In this last-mentioned method the molasses tends to accumulate or conglomerate bunches of the comminuted roughage, and complicated and expensive apparatus is ordinarily required for turning the roughage and providing a distribution of the molasses. To the best of my knowledge, all methods wherein the molasses has been mixed with the feed while the feed is being comminuted have resulted in failure, such as clogging the grinding or comminuting apparatus.

The present invention contemplates a novel system for mixing molasses with livestock feed, and particularly a roughage-type feed, with a minimum of apparatus and in such a manner that the molasses will be effectively distributed through the feed. In one embodiment of my novel system, the molasses is conducted under pressure to a spray nozzle positioned in the usual hammer mill which is utilized for comminuting the roughage. The spray nozzle is arranged in such a manner, and is so constructed, that the molasses is sprayed in a fine stream into the turbulent air created around the rotating knives or knife of the hammer mill. The spraying is accomplished when the roughage is being comminuted by the hammer mill, and the turbulent air breaks up the spray of molasses into a fine mist, whereby the molasses is efficiently mixed throughout the roughage without clinging to the interior surfaces of the hammer mill.

An important object of this invention is to economically and efficiently provide comminuted livestock feed having molasses thoroughly mixed therewith.

Another object of this invention is to provide a system of mixing molasses with livestock feed by the use of a minimum amount of apparatus.

A further object of this invention is to mix molasses with a roughage-type feed while the feed is being comminuted.

A still further object of this invention is to provide a system of mixing molasses with livestock feed which requires a minimum of skill in the control of the system.

Other objects and advantages of the invention will be

2

evident from the following detailed description, when read in conjunction with the accompanying drawings, which illustrate my invention.

The drawings:

5 Figure 1 is a diagrammatic flow diagram of a system of mixing molasses with livestock feed in accordance with this invention.

10 Figure 2 is a perspective view of the preferred apparatus of this invention.

15 Figure 3 is a detailed sectional view of the spray nozzle used for spraying the molasses.

Figure 4 is a sectional view of the hammer mill shown in Fig. 2 as taken along a vertical plane through the inlet chute in close proximity with the inlet side of

15 the mill.

Referring to the drawings in detail, and particularly Figure 2, reference character 4 designates a hammer mill of the usual type utilized for comminuting a roughage-type cattle feed. A loading chute 6 extends outwardly 20 and slightly upward from one side of the hammer mill 4 for receiving the bulk roughage, and cover 8 extends over the chute 6 adjacent the hammer mill 4. The drive shaft 10 of the hammer mill 4 has a plurality of endless belts 12 extending therearound and leading from any suitable driving mechanism, such as a tractor or the like (not shown). In the usual construction, the hammer mill 4 is mounted on a base 14 which extends to, and is arranged to be lifted by, a tractor or the like (not shown), whereby the hammer mill 4 may be moved where desired 30 for comminuting the roughage at the location where the roughage is to be used.

A bracket 16 is secured on one end 18 of the hammer mill 4 for supporting a suitable pump 20, such as a gear pump which will pump molasses. The drive shaft 22 of 35 the pump 20 has a sheave or drive wheel 24 on the outer end thereof. A drive belt 26 extends around the sheave 24 and the drive shaft 10 of the hammer mill 4, whereby the pump 20 will be operated simultaneously with the hammer mill 4, and without the use of a supplementary driving mechanism.

The inlet 28 of the pump 20 is connected by a conduit 30 to a supply of molasses, such as a barrel 32. It is preferred that the conduit 30 extend into the lower portion (not shown) of the barrel 32, whereby the conduit will effectively pick-up the molasses as long as molasses 45 is available in the barrel, and the molasses will be circulated in the barrel, as will be more fully hereinafter set forth. It is also preferred that the conduit 30 be constructed out of a flexible material to facilitate installation in the field. The barrel 32 may be placed on the ground adjacent the hammer mill 4.

The outlet 34 of the pump 20 communicates with a T-type connector 36 having a quick-opening petcock or the like 38 on the upper end thereof. The petcock 38 is used merely for inspection purposes to determine 55 whether or not molasses is being pumped by the pump 20, and is ordinarily closed during operation of the pump. The remaining connection of the T 36 communicates with another T 40 which has a back pressure valve 42 connected to one side thereof. Pressure valve 42 is in turn connected to a return conduit 44 which leads back to the barrel 32. The remaining outlet of the T-type connector 40 has another conduit 46 secured therein. Also, a pressure gauge 48 is preferably interposed in the conduit 46 adjacent the connector 40.

65 A quick-opening valve 50 is interposed in the conduit 46 downstream of the pressure gauge 48, and is secured by a bracket 52 to the side of the inlet chute 6. The valve 50 preferably has an operating lever 54 within 70 convenient reach of the outer end of the chute 6 to facilitate opening and closing the valve 50, as will be more fully hereinafter set forth. Furthermore, it is preferred

that the valve 50 be spring-loaded in order that the valve will move to a closed position when the lever 54 is released by the operator.

From the quick-opening valve 50, the conduit 46 extends on out to the outer end of the chute 6, and then (see Fig. 4) along one side of the chute 6 down toward the hammer mill 4. As shown in Figure 3, the outer end 58 of the conduit 46 is externally threaded to receive a spray nozzle 60. The nozzle 60 may be conveniently constructed out of a pipe cap with a small aperture 62 formed in the center of the closed end of the cap. The spray nozzle 60 is positioned in the inlet chute 6 opposite and in proximity with the rotating knife 64 of the hammer mill 4. Reference character 66 designates one of several stationary shearing bars secured in the mill 4 around the inlet for the feed to cooperate with the rotor 64 in comminuting the feed. It will be observed that the nozzle 60 is positioned immediately inward of the nearest bar 66, whereby molasses sprayed from the nozzle 60 will not be directly sprayed on the bar 66.

In one embodiment of this invention that portion of the conduit 46 extending down the chute 6 is constructed out of $\frac{1}{8}$ inch pipe, and the nozzle 60 is constructed out of a $\frac{1}{8}$ inch pipe cap, with the aperture 62 being $\frac{1}{16}$ of an inch in diameter. In this embodiment, the outer end of the nozzle 60 is spaced $\frac{1}{2}$ inch from the knife 64 for spraying the molasses at substantially a right angle to the plane of movement of the knife 64. As it is well known in the art, the knife 64 is rotated at a high speed (such as 1600 R. P. M.) by the hammer mill 4, and induces a turbulent movement of air in the vicinity of the knife. I have found that when molasses is sprayed into this turbulent air, the molasses is changed into a fine mist to efficiently mix with feed, as will hereinafter appear.

Operation

In operation, the hammer mill 4 is driven by any suitable means through use of the belts 12 and drive shaft 10 to rotate the knife 64 at high speed. The pump 20 is simultaneously driven through use of the drive shaft 22, sheave 24 and belt 26 to provide a constant pumping of molasses from the barrel 32 through the conduit 30 and out the discharge or outlet 34 of the pump. This molasses is discharged through the conduits 44 and 46. As previously noted, the valve 50 will normally be in a closed position to prevent a discharge of the molasses through the conduit 46. Therefore, the molasses is circulated through the valve 42 and by-pass conduit 44 back to the barrel 32. The pressure valve 42 may be set at any desired pressure to assure that sufficient pressure will be present in the conduit 46 upstream of the quick-opening valve 50 for efficient operation of the system. With the specific embodiment previously mentioned, the valve 42 may be set at approximately 70 pounds per square inch pressure to maintain a constant pressure of 70 pounds on the quick-opening valve 50. This pressure may be visually verified or checked through use of the pressure gauge 48.

It will therefore be apparent that when molasses is not being sprayed into the hammer mill 4, the molasses is constantly circulated through the conduits 30 and 44 to provide a constant stirring of the molasses in the barrel 32 and prevent thickening of the molasses. In cool weather the molasses would become extremely thick if not constantly stirred and heated by circulation through the conduits 30 and 44.

With use of the hammer mill 4, a roughage-type feed is ordinarily ground-up or comminuted in bunches, such as arm-loads. As the operator places each bunch of roughage in the inlet chute 6, he pushes the roughage down the chute 6 into the hammer mill 4 to bring the roughage into contact with the rotating knife 64. Simultaneously, in accordance with this invention, the operator

pivots the lever 54 to open the quick-opening valve 50 and provide a discharge of the molasses through the conduit 46 and nozzle 60. As the molasses is sprayed out through the aperture 62 of the nozzle 60, it enters the zone of turbulent air around the rotating knife 64 and is broken up or distributed into a fine mist for efficient mixing with the roughage as the roughage is being comminuted. It has been found that the molasses will not cling to the interior surfaces of the mill 4 to any appreciable extent, or agglomerate the roughage in the mill, when sprayed into the mill in this manner. It is also to be noted that the roughage is violently mixed and turned while being comminuted, to facilitate the distribution of the molasses through the feed. The comminuted roughage which has been sprayed with molasses is thrown upwardly through the discharge 70 of the hammer mill 4, and is usually piled in the vicinity of the hammer mill 4 for convenient feeding to cattle or the like.

As soon as each bunch of the roughage is comminuted in the hammer mill 4, the operator releases the lever 54 and the valve 50 automatically closes to prevent a further spraying of molasses into the hammer mill. This operation is repeated for each bunch of roughage fed into the hammer mill. It will be apparent that the quick-opening valve 50 may be located in any desired position, as long as it is accessible to the operator of the hammer mill.

Summary

In the preferred embodiment (see Fig. 1), the present system utilizes a hammer mill 4 and a molasses supply 32 being connected to the hammer mill 4 through a conduit indicated at 36 and 46. The conduit 46 extends through the inlet chute 6 of the hammer mill 4 for spraying the molasses into the zone of turbulent air surrounding the hammer mill rotor. A pump 20 is connected between the conduit 36 and 46 for forcing the molasses under pressure through the conduit 46 and to the hammer mill 4. A by-pass conduit 44 is connected to the conduit 46 for providing a return of molasses to the molasses supply 32 when the molasses is not being sprayed into the hammer mill. A pressure valve 42 is interposed in the conduit 44 to retain a back pressure on the conduit 46.

The supply of molasses to the hammer mill 4 is controlled by a quick-opening valve 50 interposed in the conduit 46 for spraying the molasses into the hammer mill when and as desired. The pressure of the molasses available for spraying into the hammer mill may be constantly observed by use of the pressure gauge 48, which is interposed in the conduit 46 upstream of the quick-opening valve 50.

From the foregoing it will be apparent that the present invention provides an economical and efficient system for mixing molasses with feed which is to be comminuted and fed to livestock. The molasses is mixed with the feed while the feed is being comminuted without the use of a separate mixing apparatus. All of the apparatus required beyond that normally required for comminuting the feed consists of devices and connections readily available. It will also be apparent that operation of the present system will require a minimum of skill and instruction of the operator.

Changes may be made in the combination and arrangement of elements as heretofore set forth in the specification and shown in the drawings, it being understood that changes may be made in the precise embodiment shown without departing from the spirit and scope of the invention as defined in the appended claims.

I claim:

1. A system for mixing molasses with cattle feed, comprising a hammer mill having rotating knife means for comminuting the feed, said knife means being operable at a speed to create a zone of turbulent air therearound, a spray nozzle secured to the mill on a level with the

rotating knife means with its outlet in proximity with the rotating knife means, a molasses supply, and pressure means for conducting the molasses under pressure from the molasses supply to the nozzle, whereby the molasses is sprayed into the zone of turbulent air to mix with the feed as the feed is being comminuted.

2. A system as defined in claim 1 characterized further in that the hammer mill has an inlet chute in one side thereof for receiving the non-commminuted feed, and the spray nozzle is secured in a peripheral portion of the inlet chute and arranged to spray the molasses in the direction of movement of the non-commminuted feed. 10

3. A system as defined in claim 1 characterized further in that the nozzle is arranged to spray the molasses at substantially a right angle to the plane of rotation of the rotating knife means.

4. A system as defined in claim 1 characterized further in that said pressure means comprises a pump having an inlet and an outlet, a first conduit connecting the pump inlet to the molasses supply, a second conduit 20 connecting the pump outlet to the spray nozzle, a by-pass

conduit interconnecting said second conduit to the molasses supply, a relief valve interposed in said by-pass conduit for retaining a pressure on said second conduit, and a quick-opening valve interposed in said second conduit downstream of said by-pass conduit for controlling the supply of molasses to the spray nozzle, whereby the molasses may be sprayed into the hammer mill only when feed is being comminuted.

5. A system as defined in claim 4 characterized further in that said quick-opening valve is arranged near the inlet chute of the hammer mill to be operated by the operator of the hammer mill.
